(57) CLAIM

The ornamental design for a lace fabric, as shown and described.

DESCRIPTION

FIG. 1 is a front view of a lace fabric in accordance with the present invention.

FIG. 2 is a back side view thereof.

FIG. 3 is a front perspective view thereof; and,

FIG. 4 is an enlarged detail view of the middle top area of FIG. 1.

For clarity, the lace fabric is shown upon a black background that forms no part of the claimed design.

1 Claim, 4 Drawing Sheets

FIG. 1

FIG. 4
